Patented Dec. 12, 1922.

Inventor
J. H. Milling.

By *Alfred J. Randolph Jr.* Attorney

UNITED STATES PATENT OFFICE.

JAMES H. MILLING, OF DALLAS, TEXAS.

STICK FILE.

Application filed April 18, 1922. Serial No. 554,610.

To all whom it may concern:

Be it known that I, JAMES H. MILLING, a citizen of the United States, residing at Dallas, in the county of Dallas and State of Texas, have invented certain new and useful Improvements in a Stick File; and I do hereby declare the following to be a full, clear, and exact description of the invention, such as will enable others skilled in the art to which it appertains to make and use the same.

This invention relates to a stick file.

An important object is to provide a form wherein papers or the like cannot be blown from the file particularly by the wind or blasts of air from an adjacent fan.

Another object is to provide a means which is yieldable relatively to the point of the file to permit attachment of papers or the like and which is held relatively close thereto by gravity in order to prevent normal removal of said papers or the like.

A still further object is to provide such a file with a stick member and an arm or bracket to coat therewith having means suspended therefrom to prevent removal of papers or the like normally from the stick member in combination with means on said arm to maintain the first mentioned means inactive at desirable times.

Additional objects and advantages will become apparent from a consideration of the description following taken in connection with accompanying drawings illustrating one practical embodiment.

In said drawings:—

The figure is in perspective.

Referring specifically to said figure, an upright rod, spike or file is shown at 10, sharpened at its upper end as usual, and adapted to receive papers or the like thereon as usual.

Cooperating with the stick file 10 is an upstanding arm or bracket 11, its upper portion being deflected toward the file 10 as at 12 and its upper terminal being shaped into an eyelet at 13.

The file 10 and bracket 11 may be mounted or supported in any desired way or manner. As shown, they extend from a base 14 of any suitable size or configuration or material, the base preferably being weighted.

Adjacent the penetrating or upper end of the file 10 a weight or bob 10^a is disposed, being suspended from the eyelet 13 as by 55 means of a link 16 pivotally connected thereto and in turn pivotally connected to the bob as at an eyelet 17 on the bob and an eyelet 18 on the link.

It will be realized that as the bob 15 is 60 disposed adjacent the upper end of the stick file 10, papers or the like cannot readily be displaced or blown off of the file 10 by means of wind or blasts of air as from an adjacent fan, since in upright movement of 65 the papers along the file they will engage the bob or link and thus be prevented from movement off of the free end of the file 10.

A hook or supporting element 19 is secured to the bracket 11 and as shown in dotted lines in Figure 1, the link 16 may be moved into engagement therewith so that the same will be free of the penetrating end of the file 10 and will not obstruct the application of papers or the like thereto or 75 therefrom.

Particular attention is directed to the fact that the protecting bob and link are movable by urgency of papers or the like thereagainst to attach them to file 10, thus 80 avoiding a separate step of displacing means to permit attachment of papers.

As merely one practical embodiment has been illustrated and described, it is to be understood that changes in the details may 85 be resorted to provided they fall within the spirit and scope of the invention.

I claim as my invention:—

1. A stick file having a file member, an upstanding bracket at its upper portion being deflected toward and terminating substantially over and above the file member, and means extending from and having substantially universal movement from said bracket disposed adjacent the free end of 90 said member to resist removal of filed matter therefrom.

2. A stick file having a base, a file member rising from said base, a bracket rising from said base having its upper portion deflected toward the file member and terminating in an eyelet above said member, a link suspended by and having substantially universal connection from said eyelet, a bob 100

on said link and disposed adjacent the free end of the file member to resist removal of filed matter therefrom, and a detent means on the deflected portion of the bracket engageable by said link.

3. A bill file comprising an impaling pin, a bracket extending beyond the free end of the impaling pin, a guard removably engaging over the free end of the impaling

pin, and means for suspending this guard from and for substantially universal movement relatively to the bracket.

In testimony whereof I affix my signature in presence of two witnesses.

JAMES H. MILLING.
